US0D1084129S

(12) **United States Design Patent** (10) **Patent No.:** **US D1,084,129 S**
(45) **Date of Patent:** **** Jul. 15, 2025**

(54) **MASCOT ANTHROPOMORPHIC ROBOT**

(71) Applicant: **Nabtesco Precision Europe GmbH**,
Düsseldorf (DE)

(72) Inventor: **Anne Meiners**, Essen (DE)

(73) Assignee: **Nabtesco Precision Europe GmbH**,
Düsseldorf (DE)

(**) Term: **15 Years**

(21) Appl. No.: **35/520,214**

(22) Filed: **Oct. 12, 2023**

(80) **Hague Agreement Data**

Int. Filing Date: **Oct. 12, 2023**

Int. Reg. No.: **DM/235426**

Int. Reg. Date: **Oct. 12, 2023**

Int. Reg. Pub. Date: **Mar. 8, 2024**

(57) **CLAIM**

The ornamental design for a mascot anthropomorphic robot as shown and described.

DESCRIPTION

Fig. 1.1 is a front elevational view of the mascot anthropomorphic robot showing my new design;

Fig. 1.2 is a right side elevational view of the mascot anthropomorphic robot;

Fig. 1.3 is a rear elevational view of the mascot anthropomorphic robot;

Fig. 1.4 is a left side elevational view of the mascot anthropomorphic robot;

Fig. 1.5 is a top plan view of the mascot anthropomorphic robot;

Fig. 1.6 is a bottom plan view of the mascot anthropomorphic robot;

Fig. 2.1 is another front elevational view of the mascot anthropomorphic robot; and

Fig. 2.2 is a perspective view of the mascot anthropomorphic robot, wherein articulated portions of the mascot anthropomorphic robot are shown in alternate positions.

1 Claim, 8 Drawing Sheets
